United States Patent Office.

F. A. GEISLER, OF BRISTOL, RHODE ISLAND.

Letters Patent No. 90,441, dated May 25, 1869.

REVOLVING CHRISTMAS-TREE.

The Schedule referred to in these Letters Patent and making part of the same.

To all whom it may concern:

Be it known that I, F. A. GEISLER, of Bristol, in the county of Bristol, and State of Rhode Island, have invented a new and useful Improvement in Revolving Christmas-Trees; and I do hereby declare that the following is a full, clear, and exact description thereof, which will enable others skilled in the art to make and use the same, reference being had to the accompanying drawings, forming part of this specification.

This invention relates to a new and improved device for exhibiting toys, jewelry, and other articles on Christmas eve, and at other times; and

It consists in a vertical shaft, having shelves attached thereto, with a wind-wheel on its top end, and made to revolve by rarefying the air beneath the wind-wheel, as hereinafter described.

The drawing represents an elevation of the tree, shown in perspective.

A is the central shaft, which is supported by the base, B, on a point or step at its lower end, and by a frame-work, composed of vertical or inclined posts or rods, C, which also rest on the base, and the cap-piece D, through which a spindle, E, in the upper end of the shaft passes.

A represents the shelves.

The cap is supported by the rods C, as seen in the drawing.

represents the wind-wheel, which is composed of wings attached horizontally to a central hub, and radiating therefrom, placed in an inclined position, so that an upward current of air will act upon the wheel and revolve the shaft.

G represents candle-stands, attached to the rods C, as seen in the drawing, supported by horizontal wires, which are so placed in the rods, in relation to each other, that the heat of one candle does not affect or melt any one above by the heat it generates.

The heat expands or rarefies the air, and produces an ascending current sufficiently strong to revolve the shaft and the contents of the shelves by means of the wind-wheel.

The base, B, is surrounded by a light ornamental railing, as seen in the drawing, and the whole thing may rest on legs, or stand on a table or stool, as may be desired.

I designate this a "Christmas-tree," but it is apparent that it may be used for other purposes than for Christmas occasions, as, for instance, showing jewelry, millinery, and other light articles of merchandise, in shop-windows, or in other situations.

Having thus described my invention, I claim as new, and desire to secure by Letters Patent—

The arrangement and combination of the shaft A with the shelves A', the frame, composed of the rods or posts C, cap D, base, B, and wind-wheel F, substantially as and for the purposes herein shown and described.

F. A. GEISLER.
